DESIGN FOR A FUR COLLAR

Louis Workman, New York, N. Y.

Application June 15, 1942, Serial No. 107,210

Term of patent 3½ years

To all whom it may concern:

Be it known that I, Louis Workman, a citizen of the United States of America, residing in New York city, county of New York, and State of New York, have invented a new, original and ornamental Design for a Fur Collar, of which the following is a specification, reference being had to the accompanying drawing, forming part thereof, wherein,

I claim:

The ornamental design for a fur collar, substantially as shown.

LOUIS WORKMAN.
